UNITED STATES PATENT OFFICE

2,513,383

MECHANICAL MOVEMENT

Cecil Van Armbruster, Mount Morris, Ill., and Eric Bylund, Racine, Wis., assignors to John Oster Manufacturing Company, Racine, Wis., a corporation of Wisconsin

Application February 7, 1947, Serial No. 727,040

5 Claims. (Cl. 74—48)

1

This invention relates to improvements in hair clippers of the power driven type generally referred to as electric clippers and wherein the movable cutter blade is reciprocated by an electric motor built into the body of the clipper.

In clippers of this type the drive transmission connecting the motor with the reciprocable cutter blade is an important consideration. Hence, it is an object of this invention to simplify the drive transmission and provide one which will assure smooth and quiet translation of drive shaft rotation into reciprocation of the cutter blade.

It is particularly an object of this invention to provide a drive transmission for the purpose described, which is inexpensive and easy to produce.

Another object of this invention is to reduce the weight of drive transmissions of this type to thereby enable a reduction in the total weight of the clipper.

With the above and other objects in view which will appear as the description proceeds, this invention resides in the novel combination and arrangement of parts substantially as hereininafter described and more particularly defined by the appended claims, it being understood that such changes in the precise embodiment of the herein-disclosed invention may be made as come within the scope of the claims.

The accompanying drawing illustrates one complete example of the physical embodiment of the invention constructed in accordance with the best mode so far devised for the practical application of the principles thereof, and in which:

Figure 1 is a top plan view of the forepart of an electric hair clipper embodying this invention, said view having the cover of the drive transmission housing removed;

Figure 2 is a side elevational view of the forepart of the clipper with parts broken away and in section; and

Figure 3 is a perspective view of the forepart of the clipper with the cutter head and cover for the transmission housing removed.

Referring now particularly to the accompanying drawing the numeral 5 designates the body of an electric clipper which, as is customary, is molded from a suitable plastic and houses an electric motor (not shown). The forepart 6 of the clipper housing is formed to provide a transmission housing or cavity 7 into which the motor armature shaft 8 projects. The extreme front end of the clipper body is inclined and has a cutter head 9 secured thereto by means of screws 10.

The cutter head is of conventional design and

2

comprises a stationary blade 11, through which the screws 10 pass, and a movable blade 12 held assembled with the stationary blade under the proper degree of tension by a spring 13. The spring 13 so engages the movable blade 12 as to guide the same for reciprocation across the face of the stationary blade.

An eccentric 14 is journaled on a stub shaft 15 fixed in the bottom wall of the transmission housing or cavity 7, and is driven from the armature shaft 8 by means of a worm 16 on the shaft meshing with a worm wheel 17 fixed with respect to the eccentric. The motion of the eccentric is translated into reciprocation of the movable cutter blade 12 by an actuator unit indicated generally by the numeral 18.

The actuator unit 18 consists of a length of spring steel ribbon stock bent to substantially U-shape so as to have two side arms 19 and 20 connected by a crosspiece 21. When this actuator unit is free to assume its normal shape, the side arms are parallel and at right angles to the crosspiece. The free ends of the side arms are anchored to the rear wall 22 of the transmission housing or cavity 7 by screws 23 or other suitable fastening means.

Inasmuch as the wall 22 is normal to the axis of the shaft 8 and parallel with the direction of reciprocation of the movable cutter blade it follows that the points of anchorage of the spring arms 19 and 20 are likewise parallel with the direction of reciprocation of the movable cutter blade. The points of anchorage are also so spaced as to maintain initial parallelism between the side arms 19 and 20. The side arms 19 and 20 with their connecting crosspiece 21 and the wall 22 thus define a parallelogram, which is adapted to be rocked from side to side by the eccentric.

To enable the eccentric to impart movement to the actuator unit a third spring arm 24 extends forwardly from the anchored end of the side arm 20 and is secured to the crosspiece as at 25 with the arms 20 and 24 parallel and spaced apart a distance sufficient to snugly receive the eccentric therebetween.

The crosspiece 21 is drivingly connected with the movable cutter blade 12 by a lug or tongue 26 projecting from a rigid crossbar 27 secured to the crosspiece by rivets 28. The lug or tongue 26 protrudes from the transmission housing 7 to engage in a notch or recess in the cutter blade 12 in a manner permitting ready removal of the cutter head.

55 To strengthen the actuator unit and damp out

any internal vibrations that might be set up in its spring arms and crosspiece, flanges 29 are formed on all of the spring arms and the crosspiece. These flanges stiffen the arms and the crosspiece, but, terminating short of the corners, do not preclude proper flexure as required for the back and forth motion of the parallelogram-like actuator unit.

The open top of the transmission housing is closed by a suitable cover 30 held in place by screws 31, and any suitable means not shown may be employed to seal the front of the transmission housing against the egress of the grease or other lubricant with which the transmission housing is packed.

From the foregoing description, taken in connection with the accompanying drawing, it will be readily apparent that this invention provides a simple, inexpensive drive transmission for translating rotation of the rotary power shaft of power driven hair clippers into reciprocation of the movable cutter blade.

What we claim as our invention is:

1. Transmission means for translating rotation from a power source into a reciprocating movement, comprising: an actuator unit including a rigid crossbar and opposite spaced apart spring arms of equal length joined to the bar and extending from one side thereof; attaching portions on said spring arms providing for fixedly anchoring the ends of the arms remote from the bar to a support, whereby the spring arms may be flexed laterally back and forth in unison to carry said crossbar with an endwise reciprocating motion; an eccentric adapted to be rotatably connected with the power source; means on the actuator unit embracing the eccentric so that rotation thereof effects back and forth lateral flexure of said spring arms and endwise reciprocating movement of the crossbar; and a driving lug on the crossbar.

2. Transmission means of the character described, comprising: a pair of opposite substantially parallel spring arms of equal length; a third arm joined to said spring arms crosswise of the arms and at one end thereof, said third arm being adapted to be carried by the spring arms with an endwise motion upon lateral flexure of the spring arms in consequence to the application of force to any one of said arms in the direction of the length of said third arm; attaching portions on said spring arms for fixedly anchoring the ends thereof remote from the third arm to a support while leaving the remainder of the spring arms free for lateral flexure; a rotatable eccentric connected with one of the arms for flexing the spring arms laterally back and forth in unison to thereby impart endwise reciprocating movement to said third arm; and a driving lug on said third arm.

3. Transmission means for translating rotation from a power source into a reciprocating movement, comprising: a drive arm having a driving lug thereon; means for guiding said drive arm for endwise reciprocatory movement comprising a pair of substantially parallel spaced apart arms of equal length joined at one end to said drive arm and projecting from one side thereof, and attaching portions on said parallel arms for attaching the ends thereof remote from the drive arm to a support while allowing the drive arm to move endwise back and forth relative to the support under the guidance of said parallel arms; an eccentric adapted to be rotated from the power source; and a motion transmitting connection between said eccentric and one of said arms.

4. Transmission means of the character described comprising: a rotatable eccentric; an actuator unit comprising a length of spring stock bent to substantially U shape so as to provide spaced parallel side arms connected by a crosspiece; attaching means on the actuator unit for fixedly anchoring the ends of said side arms remote from the crosspiece to a support; and means on the actuator unit embracing the eccentric so that rotation thereof imparts simultaneous back and forth flexing motion to said side arms and substantially endwise reciprocatory motion to said crosspiece.

5. Transmission means of the character described comprising: a rotatable eccentric; an actuator unit comprising a length of spring metal bent to substantially U shape so as to provide spaced parallel side arms connected by a crosspiece; a driving lug on the crosspiece; attaching means on said actuator unit for fixedly anchoring the ends of the side arms remote from the crosspiece to a support while leaving the remaining portions of the side arms free for back and forth lateral flexure in unison; and another spring arm carried by the actuator unit in spaced relationship to one of the side arms thereof and cooperating with said designated side arm to embrace the eccentric so that rotation of the eccentric imparts back and forth lateral flexure to the side arms and substantially endwise reciprocatory movement to the crosspiece.
